UNITED STATES PATENT OFFICE.

JACOB F. BENDER, OF LANCASTER, PENNSYLVANIA.

BLOWING-MACHINE.

SPECIFICATION forming part of Letters Patent No. 250,124, dated November 29, 1881.

Application filed July 13, 1881. (No model.)

To all whom it may concern:

Be it known that I, JACOB F. BENDER, a citizen of the United States, residing at Lancaster, in the county of Lancaster and State 5 of Pennsylvania, have invented certain Improvements in Blowing-Machines, of which the following is a specification.

My invention relates to improvements in blowing-machines in which the fans radiate from a shaft and revolve in a circular case; and the objects of my improvements are to so arrange a clamp and foot to sustain the fan-case that the said case can be revolved vertically, raising or depressing the mouth of the 15 same at will; and, second, to so construct the fan as to lessen the amount of air wasted. I attain these objects by the mechanism illustrated in the accompanying drawings, in which—

Figure 1 represents the fan-case and foot suspending the same; Fig. 2, a side view of the arrangement of the fan in the case; and Fig. 3, a section through *xy* of the case, as shown in Fig. 1.

Similar letters refer to similar parts throughout the several views.

The clamp *C* and foot *f* are divided into two sections, and the fan-case *A* has two lugs, *l*, projecting on each side from below. One side of the clamp *C* is secured to the bed-plate *B* by 30 means of bolts *b*. The case *A* is placed thereon with the lugs *l* of that side passing under the clamp. The other side of the clamp is then put in place under the case and secured to the bed-plate, the lugs of that side of the case passing 35 under it. The jaws *j* of both sections of the clamp are closed upon and made to firmly embrace the case by means of the bolts *b'*. To revolve the case in the clamp the bolts *b'* are loosened, and tightened again when the case 40 is in the required position.

Six fans, *H*, are secured to the fan-shaft *e* by means of flange-rings *r*, said rings being connected with the shaft by spokes *s*. The outer edges of these flange-rings lap and revolve 45 about flanges *i* of the fan-case *A*, which project inside and around the opening by which the fan-shaft passes through said case. The

fans *H* are divided into two sections, each composed of a side wing, *w*, and half of the face *n* of the fan. These side wings slope backward from the face of the fan, and are riveted to the flange *r'* of the flange-ring *r*. The wing and fan-face are in one piece; and in order to form the face of the section the metal at the angle between the two is bent back upon itself 50 for a short distance, and this doubled portion bent outward and forward, so as to form short wings *w'* for the face of the fan. The face portion is then bent toward the center, where it has a flange, *a'*, projecting forward, by means 55 of which it is riveted to a similar flange of the part of the fan-face belonging to its corresponding section. The metal of the fan is shaped so as to present a face somewhat concave. By thus lapping the flange of the case by the flange-ring *I* materially lessen the amount of air wasted, and the side wings aid in compelling the air 60 in front of the fans to pass out of the nozzle of the case, while the flange of the face both strengthens and stiffens the same.

I would further state that the air for supplying the fans is drawn in through the openings by which the shaft passes through the fan-case, and thence upward between the flange-rings into the fans, which are open below.

What I claim as my invention, and desire to secure by Letters Patent, is—

1. The clamp *C* and foot *f*, divided into two sections and having the jaws *j* and bolts *b'*, in combination with the fan-case *A*, having the 75 lugs *l*, substantially as and for the purpose set forth.

2. The combination of the flange-rings *r* with a fan case, *A*, having flanges *i*, and fans *H*, as herein specified.

3. Fans *H*, divided into two sections, each with side wings, *w*, half the fan-face and flange *a'* constructed in one piece, in combination with the flange-ring *r*, substantially as herein described.

JACOB F. BENDER.
